DESIGN FOR A FAN

Ralph E. Kruck, Springfield, Mass., assignor to
Westinghouse Electric & Manufacturing Com-
pany, a corporation of Pennsylvania

Application November 6, 1941, Serial No. 104,049

Term of patent 14 years

To all whom it may concern:

Be it known that I, Ralph E. Kruck, a citizen
of the United States, residing at Springfield, in
the county of Hampden and State of Massachu-
setts, have invented a new, original, and orna-
mental Design for a Fan, of which the following
is a specification, reference being had to the
accompanying drawings forming a part thereof.

Fig. 1 is a perspective view of a fan, taken
from the front, showing my new design;

Fig. 2 is a front elevational view thereof;
Fig. 3 is a side elevational view thereof; and,
Fig. 4 is a perspective view taken from the rear
thereof.

I claim:
The ornamental design for a fan, substantially
as shown.

RALPH E. KRUCK.
